UNITED STATES PATENT OFFICE.

ROBERT ZAHN, DECEASED, BY ALFRED RIETZSCH, ADMINISTRATOR, OF PLAUE, GERMANY.

TAMBOUR-FRAME-COUNTERBALANCING MECHANISM.

1,124,572.

Specification of Letters Patent.

Patented Jan. 12, 1915.

Application filed February 9, 1914. Serial No. 317,497.

To all whom it may concern:

Be it known that I, ALFRED RIETZSCH, a subject of the German Emperor, and a resident of Plauen, in Vogtland, in the Kingdom of Saxony, Germany, am administrator of the estate of ROBERT ZAHN, deceased, who was a subject of the German Emperor, and that said ROBERT ZAHN has invented the new and useful Improvement in Tambour-Frame-Counterbalancing Mechanism, of which the annexed is a specification.

The precision with which the tambour frame in embroidering machines moves depends entirely upon the manner in which it is suspended and also upon the distribution of the sluggish masses. With the substitution of the springs for heavy counterbalancing weights, a new problem is presented in the construction of embroidering machines, namely that of so distributing the spring forces that their actions during the movements of the tambour frame be perfectly uniform. As long as counterweights were employed counterbalancing was very simple in so far as the gravity of the counterweights was transferred by suitable rigid means to the two remotest points of the tambour frame at the right and left ends thereof. The same method could be adopted when counterbalancing is effected by springs, but the nature of springs requires that the spring forces themselves be properly divided and applied in the machine directly to the points at which they are to act. In that case it would be merely necessary to employ a proper intermediate mechanism, so as to render the movement at both ends of the tambour frame absolutely uniform.

In order that the progress made in the embroidering machine art afforded by the present invention may be fully appreciated, it is necessary to bear in mind the different actions of the two counterbalancing systems, to-wit: on one hand that of counterweights and on the other hand that of springs. With counterweight counterbalancing it is immaterial whether a single large counterweight or two weights of half the size are used, the inertia of the tambour frame and that of the counterweights will always counteract one another and thereby cause an alternate drag in one and the other direction on the stationary masses of the machine frame. This alternate action is ob-

viated with spring counterbalancing not 55 only because one half of the sluggish masses, namely that of the counterweights, is entirely done away with, but principally because there are no more sluggish masses that could counteract one another. If the right 60 half of the tambour frame is just as heavy as the left half, which ordinarily will be the case, and if both ends of the tambour frame are counterbalanced by uniform springs, then the only cause that gave rise to jerks, 65 jars, etc., has been completely removed.

My invention will be more fully understood by reference to the accompanying drawing, in which similar reference characters denote corresponding parts and in 70 which—

Figure 1 is an elevation of an embroidering machine having my new tambour frame suspension and counterbalancing device and Fig. 2 is an end view of the suspension and 75 counterbalancing device.

In the drawing, which forms part of this specification, 1 denotes the stationary machine frame and 2 the jacquard mechanism for controlling the movements of the tambour frame. The movable tambour frame 3 has the usual lateral brackets or rails 3' whereby it is adapted to be suspended in a floating manner in the machine frame so that the same may receive universal movements 80 in a vertical plane in order that all operations required for producing embroidery work can be easily accomplished. At each end and at a high point the machine frame is provided with brackets 4 in which are 85 borne rotary shafts 5 and 6, arranged parallel and above one another.

Since the suspension and counterbalancing mechanisms at both ends of the machine are identical in structure and operation, I shall describe in detail only one of them, it being understood that the description applies to both. Loosely on the spindle 5 is a gear 7 and fixed on said shaft is a cam disk 8. A coil spring 10 is connected with 95 one end to the ratchet gear 7 and at the other end to the disk 8, the gear serving for the adjustment of the tension of the spring. Keved on the spindle 6 is a cam disk 8', which is arranged in a vertical plane 100 with the cam 8 and is connected to the latter by a steel band 9, mounted around and fastened to their circumferences. The two

cams coöperating together in well known manner are adapted to afford uniform action of the spring 10. Fixed on the shaft 6 is a circular disk 11 to the circumference of which is fixed a steel band 12, the other end of which is connected to a steel band 13 which is guided over a pulley 14 suitably supported in a stationary part of the machine and which band 13 with its free end 10 carries a forked-shaped member 15. This latter is vertically guided upon stationary vertical rods 16 and carries a roller 17. The tambour frame 3 rests with its lateral arms 3' on the rollers 17 of the members 15. 15 Supported on the shaft 6 are pulleys 18 connected by an endless steel band 19, which serves for the transmission of synchronous movement from one pulley to the other. It will be seen that by this arrangement the tambour frame is perfectly counterbalanced. The band 19 may be guided over guide rollers 20 supported in brackets 21 fixed to the frame.

What I claim and desire to secure by 25 Letters Patent is:

1. In an embroidering machine, a tambour frame, a tambour frame suspension and counterbalancing mechanism, comprising a spring at each end of said tambour frame, hangers acted upon by said springs and carrying the tambour frame, a rotary shaft at each end of the tambour frame, each shaft being acted upon by the corresponding spring, and a band or wire con-

necting said shafts and securing synchronous movement thereof. 35

2. In an embroidering machine, a tambour frame, a tambour frame suspension and counterbalancing mechanism, comprising a spring at each end of said tambour frame, hangers acted upon by said springs and carrying the tambour frame, a rotary shaft at each end of the tambour frame each shaft being acted upon by the corresponding spring, spring compensating means interposed between said shafts and springs, and a band or wire connecting said shafts and securing synchronous movement thereof. 40

3. In an embroidering machine, a stationary frame, a tambour frame, a tambour frame suspension and counterbalancing mechanism, comprising a spring at each end of said tambour frame, hangers acted upon by said springs and carrying the tambour frame, a rotary shaft supported at a high point on the stationary frame and arranged at each end of the tambour frame, said shafts being acted upon by said springs, and a band or wire connecting said shafts and securing synchronous movement thereof. 45

In testimony whereof I affix my signature in presence of two witnesses.

ALFRED RIETZSCH,
*Administrator of the estate of Robert Zahn,
deceased.*
